CLAIM

The ornamental design for a computer mouse, as shown and described.

DESCRIPTION

FIG. 1 is a perspective view of a computer mouse showing my new design, on an enlarged scale;

FIG. 2 is a front elevational view thereof;

FIG. 3 is a rear elevational view thereof;

FIG. 4 is a top view thereof;

FIG. 5 is a bottom view thereof; and,

FIG. 6 is a right side elevational view with the left side being a mirror image thereof.

The broken line showing of an electrical cord in FIGS. 1 and 6 is for illustrative purposes only and forms no part of the claimed design.
